BOTTLE

Bruce L. Roberts, Rossford, Ohio, assignor to Owens-Illinois Glass Company, Toledo, Ohio, a corporation of Ohio

Filed Mar. 22, 1965, Ser. No. 84,379

Term of patent 14 years

(Cl. D58—8)

FIG. 1

FIG. 2

The side and back not shown are the same as the side and front shown. The characteristic features of this design reside in the configuration shown in full lines on the drawing.

I claim:

The ornamental design for a bottle, substantially as shown and described.
